DISPENSER FOR ADHESIVE TAPES

Vincent L. De Luisi and Charles F. Murtaugh,
Columbus, Ohio

Application September 27, 1946, Serial No. 699,720.

3 Claims. (Cl. 242—55.5)

1
The present invention relates to dispensing apparatus, and more specifically to dispensers of the type adapted to receive and dispense rolled adhesive tapes.

The general object of this invention is to provide an inexpensive, compact and mechanically efficient holder and dispenser for rolled adhesive tapes of the type commonly referred to as "Scotch tape."

The use of cellulose adhesive tapes has become increasingly popular in the present day shops, offices and department stores for sealing or securing package wrapping paper and various cartons, as well as repairing torn articles, or adhesively uniting articles of different material to one another. Tapes of this character are generally provided with an extremely sticky adhesive surface which makes the handling of the tape extremely difficult under ordinary conditions, as the tape tends to adhere firmly to the hands and fingers of a user when applying the same to surfaces to be joined.

It is also desirable to maintain tape of this character in a clean condition, as dirt or other foreign particles will quickly adhere to the sticky surface of the tape and consequently impair the adhesive qualities thereof.

Ordinarily, adhesive tapes are supplied in continuous lengths which are wound or rolled about a tubular core or spool of cardboard, or other suitable material with the sticky surface of the tape positioned to the center of the roll, thus protecting this surface from dirt, and from becoming dried by the atmosphere; but the problem of handling the tape still manifests itself even when so rolled.

Accordingly, the present invention provides a hollow cylindrical container adapted to receive a roll of such tape and to dispense the same through an opening provided in its outer curved surface in a manner to preclude unnecessary handling by the user; the container being further provided with a cutting edge which conveniently enables the user to cut a desired length of tape without further handling.

For a further and more detailed understanding of the present invention, reference is made to the following description and appended drawing wherein:

Fig. 1 is a perspective view of the improved tape dispenser;

Fig. 2 is a transverse vertical sectional view taken through the dispenser;

Fig. 3 is a longitudinal vertical sectional view thereof;

2
Fig. 4 is a perspective view of one of the semicircular shells which forms the lower portion of the dispenser;

Fig. 5 is a detailed side elevational view of the cutting lip of the dispenser;

Fig. 6 is a detailed front elevational view thereof.

Referring now to the drawing, it will be noted that the improved tape dispenser embodies a pair of hollow semicircular shells 10 and 11 respectively, which are adapted to be mated along their flat edges to form a substantially hollow cylinder, as shown in Fig. 1. Preferably, the shells are formed from an inexpensive synthetic resin of either a thermoplastic or thermosetting type, such as cellulose or vinyl base resins.

Each of the shells are formed at their flat side walls with a pair of oppositely disposed inwardly projecting semicircular ledges 12 which, when the shells are joined, form a pair of circular hubs. The ledges 12, when joined, serve to project inwardly of the ends of a cylindrical paperboard or cardboard core 13 which core serves as a foundation for the continuous roll of adhesive tape 14. Upon insertion of the rolled tape within the shells, the lower shell 11 of the dispenser is resiliently spread by pressing inwardly upon its upper peripheral edges so as to expand the side walls and the ledges 12, at which time the roll is inserted so that the ledges will register with the core 13, and the ledges are allowed to return to their normal positions by releasing the compressive forces upon the shell. The upper shell 10 is also squeezed to extend its side walls and positioned upon the lower shell with its ledges positioned in registration with the remaining opening of the circular core 13. The compressive forces on the upper shell are then released and its ledges will project inwardly of the core so as to rotatably maintain the rolled tape within a substantially enclosed cylinder.

In detaching the two shells to remove the core, the above process is repeated so as to expand the ledges and withdraw the same from within the ends of the core 13.

The lower shell 11 is recessed as at 15 at one of its adjoining peripheral edges to form a slot 16 with the adjoining edge of the upper shell 10. This slot serves as an opening through which an end of a rolled tape 14 may be passed and drawn out of the cylinder. An arcuate lip 17 is positioned adjacent to the slot 16 and extends downwardly over the peripheral edge of the lower shell 11. The lip is joined with the material 55 of the lower shell by cementing, or suitably join-

ing the same in a manner so as to firmly adhere to the outer peripheral surface of the shell. The upper end of the lip 17 extends slightly inwardly of the opening to form a downwardly directed opening for guiding the end of the rolled tape in a substantially tangential manner over the outer surface of the lip. The lower end of the arcuate lip 17 terminates in a substantially tangential plane with respect to the bottom of the lower shell 11, and is provided with a metallic cutting edge 18 secured thereto by means of rivets or screws 19.

In operation, the rolled tape is positioned first within the lower shell 11 around its ledges 12, at which time the end of the tape is drawn outwardly through the slot 16 and over the arcuate lip 17. At this time, the upper shell 10 is positioned in mating engagement with the lower shell with its inwardly directed ledges 12 projecting within the ends of the core 13. In this manner, the core will serve to hold the two shells in relative engagement and will prevent the same from being accidentally separated. When it is desired to use a length of the adhesive tape, the free end may be applied to the surfaces to be joined and the remaining length withdrawn from within the cylinder and cut or torn across the cutting edge 18. It will be manifest that the remaining end of the rolled tape will adhere to the arcuate lip and will be accessible for subsequent use. In this manner, the tape may be applied to surfaces independent of handling by the user, with the exception of initially detaching the end of the tape from the arcuate lip 17.

In view of the foregoing, it will be seen that the present invention provides a greatly simplified and useful dispenser for rolled tapes of various kinds. The dispenser serves as a convenient means of maintaining the tape in a clean and dry condition, and precludes unnecessary handling during joining operations. While the present invention has been described primarily as a dispenser for so-called "Scotch tapes," the same is equally adaptable for use with medical adhesive tapes, friction tape, and various other forms of insulating tapes. The invention is characterized by its ease of operation, structural simplicity and its economy of manufacture.

While a preferred embodiment of the present invention has been described in detail, it will be manifest that various modifications are possible without departing from the spirit of the invention or the scope of the following claims.

We claim:

1. A dispenser for rolled tape of the type pro-

vided with a central tubular core comprising a pair of mating semicircular shells adapted for detachable connection with one another to form a substantially hollow cylinder, each of said shells being formed with a pair of inwardly projecting semicircular ledges adapted to form circular end hubs with the corresponding edges of the opposite shell when the two shells are connected, said hubs being adapted for insertion within the respective ends of said core to rotatably maintain the rolled tape within said cylinder, one of said shells being recessed along one of its adjoining peripheral edges to form a slot through which an end of the rolled tape may pass exteriorly of said cylinder, and a cutting edge carried by the outer curved surface of one of said shells.

2. A dispenser for rolled tape of the type provided with a central tubular core comprising a pair of hollow semicylindrical shells open along their diametrical edges, each of said shells being formed with oppositely disposed inwardly projecting semicircular ledges adapted to form a pair of circular hubs with the corresponding ledges of the opposite shell, said hubs being adapted for insertion within the ends of the tubular core of said tape, said hubs when so inserted serving to hold said shells in relative mating engagement and to rotatably maintain said rolled tape within said shells, and a slot formed in the peripheral wall of one of said shells, said slot serving as an opening through which an end of the rolled tape may be passed exteriorly of said shells.

3. A dispenser for rolled tape of the type provided with a central tubular core comprising a pair of hollow semicylindrical shells open along their diametrical edges, each of said shells being formed with oppositely disposed inwardly projecting semicircular ledges adapted to form a pair of circular hubs with the corresponding ledges of the opposite shell, said hubs being adapted for insertion within the ends of the tubular core of said tape, said hubs when so inserted serving to hold said shells in relative mating engagement and to rotatably maintain said rolled tape within said shells, a slot formed in the peripheral wall of one of said shells, said slot serving as an opening through which an end of the rolled tape may be passed exteriorly of said shells, and a cutting edge carried upon the outer peripheral surface of one of the shells over which the tape may be drawn for severance.
